Atty.

UNITED STATES PATENT OFFICE

CHARLES HUGH DUFFY, OF MIAMI, FLORIDA

RADIO LOUD SPEAKER

Application filed October 8, 1930. Serial No. 487,211.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

- 5 (5) This invention relates to radio loud speakers and the like, and has for its object to improve the physical appearance of the same so as to render the speaker more appealing to the eye.
- 10 (10) In the design and construction of radio loud speakers, attention, for the most part, has been directed to improvements in their tonal qualities, while the esthetic and artistic characteristics have generally received little consideration.

While the ability of a radio loud speaker to faithfully reproduce sound is always of primary importance, I have found that this most important characteristic can be combined in a structure of high artistic value and striking eye-appeal.

The inventive purpose of this invention is to create the definite optical effect of two glowing columns in the opaque front of the speaker cabinet.

Referring to the accompanying drawings which illustrate one embodiment of the invention:

Fig. 1 is a front elevation of a radio cabinet 30 with speaker installed in operative position;

Fig. 2 is a vertical sectional view through the same, and

Fig. 3 is a horizontal sectional view.

Like numerals of reference indicate the same parts throughout the several figures, in which:

1 indicates a radio cabinet, 2 is the receiver, and 3 is the diaphragm of the loud speaker disposed in an opening in the opaque front of the cabinet. The diaphragm 3 is preferably of roll formation constructed of two membranes 4 and 5 secured at their edge portions 6 and flexed in quarter-circle formation so that the side edges of the two membranes lie at right angles to the plane of the central meeting edge portions thereof, as shown in Fig. 3. While this example of the diaphragm structure is preferred, any roll formation which lends itself to the accom-

plishment of the inventive purpose may be employed.

The diaphragm is made of a suitable transparent or translucent material such as sheet celluloid or the like which is preferably frosted so as to freely permit the passage of light through the same and defuse the light so as to glow.

Behind the transparent or translucent diaphragm 3 and preferably in line with the central longitudinal axis thereof, I provide one or more small electric lights 7 preferably colored, for instance a deep red color. This electric light or lights are preferably in circuit with the radio receiver such as with the dial light thereof, so that they burn only when the current to the receiver is turned on, though obviously they may be fed from a separate source of current such as by an electric battery.

Having thus described the several parts of the invention, its operation is as follows:

When the receiver is at rest, the diaphragm 3 presents only its usual physical appearance. As soon, however, as the current is turned on to the receiver 2, the electric light or lights 7 behind the transparent or translucent diaphragm 3 become lighted and, if colored, cause the preferably frosted diaphragm to take on a soft colored glow, which glow continues as long as the receiver is in operation and stops when the current to the receiver is cut off.

The effect of this soft glowing diaphragm is extremely pleasing and attractive and lends a warmth and lively artistic effect which particularly appeals to the esthetic sense.

This is exceptionally striking when the transparent or translucent diaphragm 3 is flexed in the form shown in the example illustrated in the drawings. The lights and shadows create the effect of two softly glowing cylinders or columns in the opaque front of the cabinet.

Having thus fully described the invention, what I claim as new and desire to secure by Letters Patent of the United States, is:

1. A sound reproducing system for radio loud speakers or the like, including a cabinet having an opaque front, the front of the cabi-

net having an opening therein, a diaphragm of translucent material arranged at the said opening in the opaque front of the cabinet, the translucent diaphragm being flexed into two roll formations having meeting portions centrally of the said opening, and a source of light within the cabinet and disposed to cast its rays upon the diaphragm to illuminate the two rolled formations of the diaphragm to cause the same to appear in the form of two glowing columns within the said opening in the opaque front of the cabinet.

2. A sound reproducing system for radio loud speakers or the like, including a cabinet having an opaque front, the front of the cabinet having an opening therein, a diaphragm of translucent celluloid arranged in the said opening in the opaque front of the cabinet, the translucent diaphragm being flexed into two roll formations having meeting portions centrally of the said opening, and a source of light within the cabinet and disposed behind the central meeting portions of the diaphragm to illuminate the two roll formations of the diaphragm to cause the same to appear through the said opening in the opaque front of the cabinet in the form of two glowing columns.

3. A sound reproducing system for radio loud speakers or the like, including a cabinet having an opaque front, the front of the cabinet having an opening therein, a diaphragm of translucent material arranged at the said opening in the opaque front of the cabinet, the translucent diaphragm being flexed into two roll formations having meeting portions centrally of the said opening and a source of light within the cabinet and disposed behind the central meeting portions of the diaphragm to illuminate the two roll formations of the diaphragm to cause the same to appear through the said opening in the opaque front of the cabinet in the form of two glowing columns.

4. A sound reproducing system for radio loud speakers or the like, including a cabinet having an opaque front, the front of the cabinet having an opening therein, a diaphragm of translucent celluloid arranged at the said opening in the opaque front of the cabinet, the translucent diaphragm being flexed into two roll formations having meeting portions centrally of the said opening, and a source of light within the cabinet and disposed to cast its rays upon the diaphragm to illuminate the two roll formations of the diaphragm to cause the same to appear in the form of two glowing columns within the said opening in the opaque front of the cabinet.

60 In testimony whereof I affix by signature.
CHARLES HUGH DUFFY.
